UNITED STATES PATENT OFFICE.

FRANK E. BROWNE, OF LOS ANGELES, CALIFORNIA.

DESIGN FOR A LAMP-STOVE.

SPECIFICATION forming part of Design No. 25,396, dated April 14, 1896.

Application filed May 4, 1893. Serial No. 473,022. Term of patent 7 years.

To all whom it may concern:

Be it known that I, FRANK E. BROWNE, a citizen of the United States, residing at Los Angeles, in the county of Los Angeles and State of California, have invented and produced a new, useful, and original Design for Lamp-Stoves, of which the following is a specification, reference being had to the accompanying drawings, which illustrate my design.

Figure 1 is a perspective front view of the stove which embodies my design. Fig. 2 is a side elevation of the same.

The characteristic features of my design for a lamp-stove consist in the lamp-stand made up of the base-plate A, having a lamp-seat a'' and hand-holes $a' a'$ at opposite sides of the lamp-seat a'' , arranged opening into such lamp-seat, and having rounded and downwardly and outwardly flaring sides ornamented with scrollwork a , and the reversely curved legs A', having their upper portions rounded and curved to correspond with the downwardly-flaring corners of the sides of the base-plate and forming therewith a symmetrical outwardly-rounded curve, the stove-body comprising the semicylindrical wall B, provided with side handles D D' at the top of the wall at opposite sides of the body, and the stove-top, comprising the circular unornamented domed top piece or spun plate C, having an ogee outline c , and the closed or-

namented urn C', surmounting the plate C. The wall B is semicylindrical throughout its entire length from the base-plate A to the top piece C. The top piece is circular and terminates flush with the wall.

The characteristic features of the particular design for a stove-top consist in the unornamented domed top piece or spun plate C, having an ogee outline c , in which there is a single offset c' , and the closed ornamented urn C', surmounting the plate C.

The characteristic features of the particular design for the base-plate consist in the hand-holes $a' a'$ at opposite sides of and opening into the lamp-seat a'' .

The characteristic features of the particular design for the stove-body consist in the wall semicylindrical throughout its entire length and the handles arranged at the opposite edges of the semicylindrical wall, as shown.

E indicates a lamp seated in the lamp-seat a'' .

Now, having described my design, what I claim as new, and desire to secure by Design Letters Patent, is—

The design for a lamp-stove substantially as herein shown and described.

FRANK E. BROWNE.
